C. L. HUDLER.

WATER HEATER.

APPLICATION FILED DEC. 6, 1915.

1,276,065.

Patented Aug. 20, 1918.

Fig. 1.

UNITED STATES PATENT OFFICE.

CHARLES L. HUDLER, OF ST. LOUIS, MISSOURI, ASSIGNOR, BY MESNE ASSIGNMENTS, TO JIFFY WATER HEATER COMPANY, OF ST. LOUIS, MISSOURI, A CORPORATION OF MISSOURI.

WATER-HEATER.

1,276,065.

Specification of Letters Patent. Patented Aug. 20, 1918.

Original application filed July 6, 1915, Serial No. 38,381. Divided and this application filed December 6, 1915. Serial No. 65,272.

To all whom it may concern:

Be it known that I, CHARLES L. HUDLER, a citizen of the United States, and resident of St. Louis, Missouri, have invented certain

5 new and useful Improvements in Water-Heaters, of which the following is a specification containing a full, clear, and exact description, reference being had to the accompanying drawings, forming a part hereof.

10 My invention relates to improvements in automatic water heaters, and the object of my improvements is to construct a water heater in compact form, inexpensive in design, and economic in its consumption of 15 fuel.

This application is a divisional application from my application filed July 6th 1915, Serial Number 38,381.

To the above purposes, my invention consists in certain novel features of the construction and arrangement of parts which will be hereinafter specifically described, pointed out in my claim, and illustrated by the accompanying drawings, in which—

25 Figure 1 is a vertical sectional elevation of the complete water heating apparatus, and

Fig. 2 is an enlarged plan, partly in section, showing the construction, and arrangement of the water bodies and the damper operating means.

Referring by numerals to the accompanying drawings, 7 designates a double walled shell or drum, between which double walls 35 water to be heated is circulated, and through which shell heat is directed.

This shell is preferably open bottomed, and supported above the floor on a base 8 so that water controlling and heating devices may be installed beneath the shell.

Between the double walls at their upper and lower ends, I insert rings 9, which close the ends of the space between said walls. Through the outer wall near its bottom I 45 provide a nipple 10 and connect therewith a service pipe 11 leading from a source (not shown) of water supply under pressure.

Through the inner wall of the shell near its top and preferably diametrically opposite the nipple 10 is a nipple 11^a, extending into the shell 7 for connection with a train of hollow baffles 12, which are all of like construction, except for size, and in this

respect it is preferable that the baffles be of greater water capacity and cover a greater area at the top of the train than at the bottom.

To the lowermost baffle I connect a pipe 13 leading to a water box 14. Connected with the water box is a cylinder 17, which communicates with the box and in which there is a piston (not shown) connected with the rock shaft 15.

In communication with pipe 13 is a pipe 19 having a valve 20 from which hot water is drawn. As shown in Fig. 2, each baffle is semi-disk shaped and has on its interior a wall 20^a extending at an angle from the approximate longitudinal center of the straight side of the baffle toward, but not to, the opposite round wall of the baffle.

Through the upper and lower walls of each baffle and on each side of the wall 20^a there is a tapped opening into which nipples 21 are threaded for the connection of the various baffles *en train*.

Over the top of the drum or shell 7, I provide a cap 22 and connect therewith a flue 23, which carries off the surplus heat after having passed through the shell and conducts it from the heater in a common manner.

The flue 23 is provided with a damper 24, whose shaft is provided with a crank 25 for its operation.

The numeral 26 designates a gas pipe which extends to and beneath the shell 7, whereat is secured a reducing nipple 27, and secured to the nipple 27 is a cap 28.

Rotatably supported on top of the cap 28 is a head 31 comprising a series of tubes 36, each of which tubes is open topped and have intermediate their ends the air mixing ports 37. The head 31 has at diametrically opposite sides the laterally projecting arms 38, by means of which the head may be rotated for turning on and off the gas to the burners. One of the arms 38 has connected thereto a link 40, and this link 40 connects directly with a vertically disposed bell crank 41 connected with the crank shaft of the damper.

In the gas pipe adjacent the combined valve and burner, I provide a T-coupling 44, for the purpose of connecting a pilot tube 105, whose upper end lies in proximity to the

upper ends of the tubes 36 and which pilot includes a valve 46, whereby to control the volume of gas passing therethrough.

In the end of the cylinder 17 extending 5 into the path of movement of the piston is a set screw 49, which may be adjusted to vary the stroke of the piston to control the flow of water.

The water is admitted to the water heating chamber through the pipe 11, and the heat generated by the burner being circulated upward through the shell will heat the water within the double walls thereof, as well as the water in the hollow baffles. The 10 water brought into the shell at its bottom rises upwardly through the double walls and downwardly through the train of baffles and thence to the point of discharge. By reason of the water being conducted 15 downwardly through the hollow baffles, there is little or no danger of the baffles being clogged by sediment, because of their being continuously flushed in a downward direction. By operating the gas valve 31 the gas 20 is turned on and off as desired and the operation of the gas valve controls the damper 24.

Having thus described my invention, what I claim as new therein and desire to secure 25 by Letters-Patent of the United States therefor is—

A water heater comprising a double

walled shell open at its bottom and damper controlled at its top, the walls of said shell being spaced apart so as to form an unobstructed water chamber, a water supply pipe connected to the lower end of the shell, a plurality of hollow bodies connected in train and of progressively decreasing size from the upper to the lower end of the train, each 30 body being spaced apart from each other and from the shell and provided with parallel upper and lower walls and a side wall comprising an arcuated portion and a plane portion and a partition connecting the upper and lower walls and plane wall and spaced from the arcuated wall, tubular connections connected with the upper and lower walls and on opposite side to said partition, a valve controlled outlet connected to the lowermost one of the heating bodies, a connection between the uppermost one of the heating bodies and the water chamber of the shell, and a gas burner positioned beneath the shell and arranged to discharge heat upwardly through the shell and around the heating bodies.

In testimony whereof, I have signed my name to this specification, in presence of two subscribing witnesses.

CHARLES L. HUDLER.
